UNITED STATES PATENT OFFICE.

JOHN W. SMITH, OF PHILADELPHIA, PENNSYLVANIA.

PROCESS OF AND DEVICE FOR VAPORIZING LIQUID FUELS.

Application filed November 20, 1920. Serial No. 425,533.

To all whom it may concern:

Be it known that I, JOHN W. SMITH, a citizen of the United States, residing in Philadelphia, in the county of Philadelphia and State of Pennsylvania, have invented certain new and useful Improvements in the Processes of and Devices for Vaporizing Liquid Fuels, whereof the following is a specification, reference being had to the accompanying drawings.

The invention relates in part to an improved process or method of effecting complete and efficient vaporization of commercial liquid fuels, such as the hydrocarbons employed in operating internal combustion engines, and in part to devices by aid of which this process may be economically carried out.

In the production of commercial liquid fuels now on the market, the temperature at the end of the distillation is often above 350° F., so that in order to effect complete vaporization of the fuel for use in an internal combustion engine, it has been customary, heretofore, to heat a portion of the intake manifold to a high temperature (within a range of from 500° F. to 1000° F.) at a region where the less volatile, higher boiling portion of the fuel was caused to accumulate. As a result, the whole volume of the mixed air and fuel was raised to such a high temperature as to greatly impair the efficiency of the engine. Many attempts have been made to obtain a fuel mixture of low temperature, from 100° F. to 150° F., under the above outlined principle of carburation, but this has been found absolutely impossible.

The primary object of my invention is to overcome this difficulty. This I accomplish to the best advantage by vaporizing the more volatile or lower boiling portion of the fuel at the lowest possible temperature, segregating the unvaporized liquid portion of the fuel, separately vaporizing this latter portion (apart from the rest) at a very high temperature and returning this less volatile portion in a vaporous condition to mingle and combine with the aforesaid more volatile portion on its way to the engine cylinders.

Both my improved process, and the device which I employ in practicing the same will be readily understood from the detailed description which follows.

In the accompanying drawings, Fig. I is a plan view of a vaporizing device convenient for the purposes of my invention.

Fig. II is a sectional view of the device in association with a carburetor and with the exhaust manifold of an internal combustion engine.

Figs. III and IV are plan sectional views, the horizontal planes of which are indicated respectively by the arrows III—III and IV—IV in Fig. II.

My improved device is applicable as an auxiliary to any standard type of carburetor, so that no showing of a carburetor is here required save the outlet indicated at 1 in Fig. II. This outlet is governed or controlled in the usual manner by a throttle valve 2 under the actuation of a control lever 3. Superposed as an axial continuation of the carburetor 1 is a vertical, cylindrical element 5. The bore of this element 5 is somewhat larger in cross section than the carburetor outlet, and is approached through a divergent flare shown at 6. In passing through the element 5, the air and liquid fuel mixture from the carburetor is permitted to expand somewhat, and caused to swirl by a stationary spiral deflector element 7. The turbulence or agitation thus produced serves to facilitate vaporization of the more volatile portion of the fuel and separation of the unvaporized portion as will hereinafter be more fully explained.

The element 5 is, in turn, surmounted by a fitting 8 formed with a neck 9 aligned as an axial continuation of the element 5. These parts 5 and 9 form a portion of the main intake conduit of the engine. The top of the neck 9 is appropriately faced, and provided with bolt holes 10 for the attachment of the intake manifold of the gas engine, indicated at 11 in Fig. II. The fitting 8 has a shallow, hollow, rectangular vaporizer casing in the form of a laterally projecting offset or extension 12. This casing extension 12 is internally subdivided by a horizontal diaphragm or partition 13 which terminates short of the outer plugged end 14 of the extension, as best shown in Fig. II, and thus forms in the casing a by-pass which comprises the inlet and outlet branches 15 and 16. In the inlet branch 15 of the by-pass are short spaced vertical partitions 17 and 18, whose forward ends are tapered and curved, as best shown in

Fig. IV and an inwardly extending projection 19 serve a purpose which will be later explained. On the bottom of the inlet pass 15 (as here shown at about the region of the partitions 17, 18) is a transverse dam, in the form of a downward offset of the floor, over which the fuel traversing said pass falls or cascades. In the branch 16 is likewise a single, central, vertical partition 20 of somewhat greater linear extent than the partitions of the branch 15. At their source, these branches merge respectively with semi-annular channels 21, 22 extending part way about the main conduit and separated by a nozzle sleeve 23 threaded axially into an opening in that portion of the diaphragm 13 which extends across the conduit 5.

As clearly shown in Figs. I, III and IV, the fitting 8 is formed at one side with an eccentric bulge indicated at 24 in Figs. I and II with the result that the sectional configuration of the channel 21 (Fig. IV) assumes the form of the segment of a gradually expanding spiral. The channel 22 is of the same width as the branch 16 of the by-pass, and its curved wall 25 is eccentrically disposed with respect to the sleeve nozzle 23, so as to gradually contract the passage toward the front, see Fig. III. The flattened portion 26 of the wall 25 serves as a reacting surface for deflecting the vapor from the channel 22 into the main conduit, as hereinafter described.

The lower periphery of the nozzle sleeve 23 has a lip which overhangs the top and a narrow zone of the inside surface of the element 5 with very slight clearance, thus affording a comparatively narrow, annular, trap orifice 27. Referring still to Fig. II, it will be noted that the top edge of the element 5 projects above the floor of the channel 21, so as to retain the unvaporized fuel drawn into the by-pass during the operation of the device. The lower portion of the nozzle sleeve 23 is flared as at 29, while its reduced upper end extends well into the bore of the neck 9 of the fitting 8. From the illustration, it will be noted that the annular space 30 around the reduced upper portion of the nozzle sleeve 23 is considerably larger in area than the orifice 27. As a consequence, a difference of pressure is maintained between these points under the suction of the cylinders of the engine as the main charge is drawn upwardly through the gradually contracted area of the nozzle bore. The difference of pressure thus established tends to produce rapid flow through the by-pass. If desired, this pressure difference may be controlled and regulated by a butterfly valve 31, preferably coupled, so as to be simultaneously operable with the throttle 2 of the carburetor, by means of a link 32. It is to be particularly noted that the size of the valve disk 31 as compared

with the area of the opening through the nozzle sleeve 23 is such as to have very limited throttling effect for most speeds of the engine, and none at all for high speeds. It is also to be noted that the opening 70 through the nozzle sleeve 23 is of an area equal to that of the carburetor outlet 1, and hence capable of permitting the passage of the maximum capacity of the carburetor.

In order to effect vaporization of the liquid fuel drawn into the by-pass of the extension 12, the latter is almost wholly disposed within an enlarged portion 33 of the exhaust manifold 34 of the engine (shown only in Fig. II). The enveloped portion of the extension is appropriately finned as at 35 to provide an extensive heating surface, whereby the rapidity of the evaporation is enhanced. An integral head or external flange 36 on the fitting 8 serves as a cover 85 for the opening in the manifold through which the finned end of the extension 12 is passed in assembling, and these elements are secured to each other by means of clamp bolts shown at 37.

The operation of the device is as follows:

The charge liberated by the carburetor is drawn upwardly through the outlet 1 and into the bore of the element 5 of the intake conduit, under the suction of the engine cylinders. The turbulence or agitation set up in the mixture during its passage through the element 5 not only tends to cause evaporation of the more volatile, lower boiling portion of the fuel, but also causes the unvaporized liquid fuel of higher boiling point to be separated from the more volatile portion, and collect on the walls of said element. Ordinarily, I prefer to increase this turbulence or agitation by aid of the spiral 7, which not only facilitates the evaporation of the more volatile portion of the fuel, but also causes the unvaporized accumulation to be directed upwardly toward the annular trap orifice 27, whence it finds its way into the channel 21. While the spiral deflector element 7 serves to enhance the turbulence or agitation in the intake conduit and the efficiency of the device, it is not absolutely essential, and may, if desired, be omitted. Immediately upon entering the channel 21, the liquid flows along the floor of the branch 15 of the by-pass of the extension 12. Any tendency of the liquid to gyrate under the influence of the charge passing through the structure is offset by the curved forward ends of the vertical partitions 17 and 18 and by the projection 19 of the branch 15 which catch the liquid globules released at a tangent, and thus tend to divert or deflect them and at the same time, to distribute the same, as suggested by the arrows in Fig. IV. The liquid then flows over the dam 28. As soon as it encounters the heated portion of 130

the extension 12 within the manifold 34, the liquid fuel is quickly vaporized, somewhat after the manner of a flash boiler. The vapor passes about the outer end of the dia-
5 phragm 13 and through the branch 16, and is drawn into the channel 22, whence it finally escapes through the larger annular opening 30 and re-enters the main conduit of the structure to commingle with the main
10 charge.

Under the vacuum that obtains in the engine intake 5 beyond the throttle 2, the more volatile or low boiling portion of the liquid fuel is vaporized at a minimum temperature,—materially lower than at the substantially higher pressure (approaching atmospheric) that exists below the throttle. Again, only a small part (by weight) of the air and fuel mixture entering the intake
15 passes through the heating element and this remains in the heating element only until the temperature of vaporization (under vacuum) is reached being drawn out before any appreciable rise above this point can take
20 place, so that the temperature of the gas entering the engine as a whole is very little affected by the commingling of the high temperature vapor with the main part of the charge. Owing to the relatively low
25 temperatures at which both portions (more or less volatile) of the liquid fuel are vaporized and to the small proportion vaporized at the higher temperature, the average temperature of the gas entering the engine
30 is surprisingly low. Also, this temperature is remarkably constant. Thus, I have been able to obtain an efficient dry gas which in practice has been observed to vary only between 100° and 120° Fahrenheit under all
35 conditions of motor performance, notwithstanding temperature variations between 500 and 1000 degrees in the heating element and atmospheric temperature changes of 50 degrees or more.

Having thus described my invention, I claim:

1. The process of producing, from liquid fuel, combustible vapor for internal combustion engines which consists in expanding and agitating the atomized fuel to facilitate vaporization of its more volatile constituent and isolation of the unvaporized portion, vaporizing the more volatile portion under vacuum at the lowest possible temperature, di-
50 verting the segregated less volatile portion, separately vaporizing the same under a dif-
55 ferent vacuum pressure at a very high tem-
60 perature, and thereafter combining the va-
porized more-and-less volatile portions without appreciable rise in temperature of the resultant mixture.

The process of producing, from liquid fuel, combustible vapor for internal combustion engines which consists in expanding and agitating the atomized fuel to facilitate

vaporization of its more volatile constituent and to segregate the less volatile portion, vaporizing the more volatile portion under vacuum at the lowest feasible temperature, insularily vaporizing the less volatile portion by flash action under a different degree of vacuum at a very high temperature, and thereafter combining the more-and-less volatile vaporized portions without appreciable rise in temperature.

3. The process of producing, from liquid fuel, a combined air and vapor mixture for internal combustion engines, which comprises agitation of the mingled air and fuel from the carburetor under the vacuum of the engine intake to vaporize the more volatile constituent and segregate the unvaporized portion; separately vaporizing the latter portion by flash action under the intake vacuum with a difference of pressure at a very high temperature; and thereafter combining the portions vaporized without appreciable rise in temperature of the resultant mixture.

4. A device of the character described comprising an internal combustion engine intake conduit wherethrough an air and liquid fuel mixture is drawn; and a heating by-pass, for vaporizing unvolatilized liquid fuel of said mixture apart from the rest thereof, communicating with said conduit at its inlet end through a relatively small opening and at its outlet end through a larger opening, so as to return the fuel therein vaporized straightway to said conduit and avoid overheating thereof.

5. A device of the character described comprising an internal combustion engine intake conduit wherethrough an air and liquid fuel mixture is drawn; a heating baffled by-pass, for vaporizing unvolatilized liquid fuel of said mixture by flash-action apart from the rest thereof, communicating with said conduit at its inlet end through a relatively small opening and at its outlet end through a larger opening; said conduit having its area reduced between the ends of said by-pass to cause a difference in pressure for producing flow through the latter.

6. A device of the character described comprising an internal combustion engine intake conduit wherethrough an air and liquid fuel mixture is drawn; a heating by-pass for vaporizing unvolatilized liquid fuel of said mixture apart from the rest thereof, communicating with said conduit at its inlet end through a narrow annular opening, and at its outlet end through an annular opening of relatively larger area; and a nozzle sleeve in said conduit separating the aforesaid openings and serving to maintain a difference in pressure between them for producing flow through the by-pass.

7. A device of the character described comprising an internal combustion engine

intake conduit wherethrough an air and liquid fuel mixture is drawn; a heating bypass for vaporizing unvolatilized liquid fuel of said mixture apart from the rest thereof, 5 communicating with said conduit at its inlet end through a narrow annular opening, and at its outlet end through an annular opening of relatively larger area; a nozzle sleeve; and a valve for controlling and regulating the flow through said nozzle sleeve. 10

8. A device of the character described comprising an internal combustion engine intake conduit wherethrough an air and liquid fuel mixture is drawn; a vaporizer casting projecting laterally from and communicating with said conduit internally subdivided to afford a heating by-pass for vaporizing unvolatilized liquid fuel of said mixture apart from the rest thereof; and means 15 for diverting and passing such unvolatilized liquid fuel from said conduit through said by-pass.

9. A device of the character described comprising an internal combustion engine

intake conduit wherethrough an air and liquid fuel mixture is drawn; and a flash-action baffled vaporizer projecting laterally from and communicating by a narrow orifice with said conduit, said vaporizer having vertical partitions whose forward ends are 25 tapered and curved, and an external casing for attachment to an exhaust manifold. 30

10. In a device of the character described, means affording a main air stream isolated from the vaporizer path as to surrounding 35 walls and mixture communication during the period of vaporization, said vaporizer path having a constricted inlet from the main stream and a relatively larger outlet for returning the vapor to the main air 40 stream, and said inlet and outlet being effective to produce a difference of pressure in the vaporizer whereby constant circulation therethrough obtains.

In testimony whereof, I have hereunto 45 signed my name at Philadelphia, Pennsylvania, this 17th day of November, 1920.

JOHN W. SMITH.
